DRAPERY-OPERATING SYSTEM

Thomas A. Stubblefield, 420 E. Bobier Drive, Vista, Calif., assignor of one-third each to James F. Brooks, Garden Grove, Calif., and to John H. Hancock, La Habra, Calif.

Filed Mar. 23, 1962, Ser. No. 182,063

13 Claims. (Cl. 160—345)

This invention relates to apparatus for opening and closing draperies, and more particularly to a drapery-operating system incorporating a positionable end pulley unit for use in conjunction with hollow tracks or traverse rods.

A principal object of this invention is to provide a drapery-operating system for accommodating draperies of various widths along a predetermined segment of a track or traverse rod.

Another object of this invention is to provide a drapery-operating system including a positionable and releasably-lockable end-pulley unit utilizable either to accommodate the depending runs of a drapery pull cord, or as a universal return for runs of the cord enclosed within a hollow traverse rod or track.

A further object is to provide a compact, economical and flexible drapery operating system employing any desired length of standard track or traverse rod.

An additional object of this invention is to provide a drapery-operating system including a positionable and releasably-lockable end-pulley unit to accommodate depending runs or, alternatively, to function as a universal return for a drapery pull cord, the system being such that more than one pull cord may be installed in a single track.

A further object of this invention is to provide universal end-pulley units for installation in a longitudinally-slotted traverse rod, such pulleys being suitable either for use as a universal return or as a suspension for the depending runs of a drapery pull cord, so that the depending runs of the cord may be changed from one to the other of two end pulleys without the necessity of reversing their positions, or restraining the pull cord.

Another object of this invention is to provide a drapery-operating system utilizing a positionable and releasably-lockable end-pulley unit for use with existing traverse rods, such unit being thin enough to fit within the slot of a conventional standard or heavy-duty traverse rod, and being free from structure overlapping the outer edges of the rod.

Another object of this invention is to provide a positionable and releasably-lockable end-pulley unit including a detachable return bar, such bar being adjustable in length and making it possible to fold the outer vertical edges of the draperies in conventional manner toward the vertical wall surface adjacent to the traverse rod, and to suspend the fold fixedly in this position.

These and other objects and advantages of this invention will be set forth more fully in the following specification and claims, considered in connection with the attached drawing to which they relate.

In the drawing:

FIGURE 1 is a side elevation of the positionable drapery-operating system of this invention, showing a typical installation of two of the positionable, releasably-lockable, end-pulley units on a traverse rod, with one of the units utilized as a universal cord return and the other as a drop-cord suspension;

FIGURE 2 is an enlarged view of the righthand pulley unit of FIGURE 1, illustrating the operation of the releasable locking device which makes it possible to shift the unit longitudinally along the track or traverse rod;

FIGURE 3 represents a lateral cross-section through

2

the traverse rod along the vertical plane 3—3 indicated in FIGURE 1;

FIGURE 4 is a horizontal cross-section through the end-pulley unit of FIGURE 2, taken along the horizontal plane 4—4, and illustrating more specifically the manner in which the unit is supported on the traverse rod;

FIGURE 5 is a perspective representation of one of the end pulley units, showing its external structural features; and

FIGURE 6 is a fragmentary cross-section taken along the horizontal plane 6—6 of FIGURE 3 to show a plurality of mounting holes for receiving selectively the pin or hook used to support rearward drapery folds of various lengths.

Referring to FIGURE 1 of the drawing, the positionable drapery-operating system of this invention includes two identical, positionable, and releasably-lockable end pulleys 2 shown in a typical installation on a traverse rod or track 30. The righthand end pulley 2 is shown as utilized as a drop-cord suspension device for the depending runs 35a and 35b of a drop cord 35. The lefthand pulley 2 then functions as a universal return device, the cord 35 being looped around one of the pulley wheels.

Each of the pulley units 2 is provided with a releasable cam lock 10 for securing it firmly in place at the desired location on traverse rod 30. By releasing the cam lock 10 of each pulley unit 2 in the manner explained below, these units may be slid to new positions along traverse rod or track 30. When the pulley units 2 have been positioned, for example, at their respective new locations 38 and 39, their respective cam locks 10 are actuated to engage traverse rod 30 and again secure the units firmly but releasably in place.

It should be noticed that a plurality of pairs of pulley units 2 may be installed on traverse rod 30. For example, the alternative position 38 may also be understood to represent a third pulley unit 2 functioning as a drop-cord suspension device in cooperation with the lefthand pulley unit 2. Likewise the alternative position 39 may be understood to represent a fourth pulley unit functioning as a universal-return device in cooperation with the righthand pulley unit 2. A separate pull cord 35 may be used with each cooperating pair of pulley units 2.

Each pulley unit 2 is best portrayed in FIGURES 2—5, and comprises generally a thin, channel-like frame 4 having a top wall 4a, integral sidewalls 4b and 4c, and four integral mounting flanges 4d extending laterally from the upper corners of sidewalls 4b and 4c. The frame 4 is open at the bottom and at each end.

Two pulley wheels or sheaves 6 and 8, made of plastic, metal, or other suitable material, are supported between the sides 4b and 4c of the frame 4. The wheel 6, installed for rotation around a pin 7 extending through coaxial holes provided in the frame sides 4b and 4c, may be characterized as an end wheel because the drop cord 35 never extends beyond it. The wheel 8, installed for rotation around a pin 9 extending through another pair of coaxial holes in the frame sides, may be called the intermediate wheel. The elevations of the wheels are caused to be slightly different, so that cord friction will be minimized.

The respective thicknesses of the pulley wheels 6 and 8 are equal, and slightly less than the distance between the internal surfaces of frame sides 4b and 4c. As a safeguard against the possibility that the frame sides 4b and 4c may be accidentally bent inwardly against the sides of pulley wheels 6 and 8 and prevent their free rotation, the mounting pins 7 and 9 may be provided with shoulders (not shown) to bear against the inner surfaces of sides 4b and 4c surrounding their respective mounting holes.

As represented best in FIGURES 3 and 4, the external width of frame 4 is caused to be slightly less than the width of the standard longitudinal slot or gap 31 which is provided in the lower surface of traverse rod or track 30. This makes it possible to mount the pulley unit 2 in traverse rod 30 by merely removing a suitable end plug 32, and then sliding the pulley into the slot. The mounting flanges 4d will then engage the inner track surface adjacent the opposing edges 31a and 31b of the slot. When the pulley is in this position, the extreme upper portions of the pulley wheels 6 and 8 will be within track 30, but the major portion of the frame 4 of pulley unit 2 will extend downwardly from the slot 31. The pulley wheels lie (FIGURE 3) in a plane which: (a) contains the axis of the track 30, and (b) extends through slot 31.

The cam lock 10, shown best in FIGURE 2, is mounted for pivotal movement around the end of the mounting pin 9, such end extending outwardly from the frame side 4b. The lower end of the cam lock 10 is provided with a laterally-extending handle 10a to facilitate locking and releasing the pulley unit 2. The upper edge of cam lock 10 is shaped with an arcuate portion 10b having a radius (measured with respect to the axis of mounting pin 9) which increases to a maximum slightly in excess of the distance between pin 9 and the external surface of slot edge 31a, and then diminishes abruptly to form a cam notch 10c. A biting tooth 10d is thus formed adjacent the arcuate portion 10b, as is a lock-limit corner or stop 10e.

Rotation of the handle 10a in the clockwise direction will have the effect of bringing the biting tooth 10d into engagement with the lower surface of traverse rod 30 adjacent slot edge 31a. Further clockwise rotation of the handle 10a will cause the biting tooth 10d to exert pressure against and make a slight resilient bend or depression in the slot edge 31a. When the biting tooth 10d passes over the vertical apex of its rotation around the axis of pin 9, further clockwise rotation is arrested by engagement of the lock-limit corner or stop 10e with the lower surface adjacent to the slot edge 31a, and the pulley unit 2 is locked releasably in position. The downward pressure exerted against the biting tooth 10d by the resiliently-deformed slot edge 31a maintains the cam lock 10 in the lock position shown at L.

It should be noticed that normal operation of the pull cord 35 will result in application of a longitudinal component of force directed toward the cooperating pulley unit 2 (FIGURE 1). Hence, the possibility that a longitudinal force component will be applied to the pulley unit 2 in the opposite direction and tend to unlock the cam lock 10 is virtually non-existent. The biting tooth 10d prevents the pulley unit 2 from sliding toward the cooperating pulley unit during operation of the pull cord 35 to open or close draperies (not shown) which are suspended from the traverse rod 30. In this connection, reference is made to my co-pending applications, Patent Application, Serial No. 99,112, filed March 29, 1961, now Patent No. 3,090,431 for Drapery Supporting and Pleating Apparatus, and Patent Application, Serial No. 167,824, filed January 22, 1962, for Drapery Positioning Apparatus.

To release the pulley unit 2 and prepare it for movement along traverse rod or track 30, the handle 10a of the cam lock 10 is rotated counterclockwise into release position R. This disengages the biting tooth 10d from the surface of the rod 30 adjacent slot 31a, and makes it possible to slide the pulley unit 2 longitudinally along slot 31.

In accordance with another important feature of the invention, each pulley unit 2 includes a laterally-extending drapery-return bar 40 to provide means for supporting a rearwardly-directed, vertical end fold of a drapery (not shown) which is suspended from the traverse rod 30. The return bar 40, made of metal, has a forked end 40a, an offset bend 40b, and a plurality of holes 40c respectively adjacent to lateral notches 40d (FIGURES 3 and

5 6). The forked end 40a is accommodated in laterally-opposed, parallel, vertical slots 4e (FIGURE 5) which are provided in the frame sides 4b and 4c of each pulley unit 2. The location of slots 4e is so chosen that the portion of bar 40 between the sides 4b and 4c will not interfere with cord 35.

To install the return bar 40 on frame 4, the forked end 40a is inserted through the vertical slots 4e. The prongs of the forked end 40a are then deformed or staked slightly to engage the edges of such vertical slots, thus preventing the bar 40 from becoming detached from its associated frame in normal use.

The lateral notches 40d (located adjacent the respective holes 40c) make it possible to break off end portions of the return bar 40 in order to shorten it to a length appropriate for the width of the rearward fold of the drapery (not shown), as determined by the distance between track 30 and the wall. The holes 40c accommodate the hook or other device utilized in an obvious manner to suspend the drapery fold from the return bar 40. Holes (not shown) for additional hooks are formed in frame sides 4b and 4c. The offset bend 40b positions the supporting end 40e of the bar 40 so that the rearward fold of the drapery will conceal the pulley unit 2.

It should be noticed that it is possible to reverse the functions of the two end pulleys, it being unnecessary to remove the pull cord 35 from the traverse rod 30 or to remove the draperies. Referring to FIGURE 1, the function of the lefthand pulley unit 2 may be changed from that of a universal return device for the pull cord 35 to that of a drop-cord suspension unit merely by grasping the cord portion 35c and pulling it downwardly to form drop-cord runs like the runs 35a and 35b depending from the righthand pulley unit 2. Hence, the righthand pulley unit 2 ceases to function as a drop-cord suspension device, and begins instead to function as a universal return device.

Although the pulley units have been referred to as identical, it is pointed out that the return elements 40 are inserted therein from opposite sides thereof. The previously described unit 2 is the one shown at the right in FIGURE 1, and also in FIGURES 2-5. In the unit 2 represented at the left in FIGURE 1, the return 40 is disposed on the same side of track 30 as is the return shown in FIGURES 2-5. However, such left unit 2 is turned around in such manner that the cam lock 10 is disposed on the remote side of its frame 4, not on the adjacent side as is the case relative to the right pulley. Thus, the two pulley units 2 are mirror images of each other (the mirror being located intermediate the pulleys and perpendicular to track 30) except that locks 10 are on opposite sides of their associated frames.

The relationship described in the previous paragraph permits use of identical frames 4 and associated wheels and locks, with consequent economy of manufacture. The relationship produces the advantage that the more elevated pins or shafts 7 are remote from each other (the lower shafts 8 being intermediate), so that cord friction is minimized. Furthermore, and very importantly, the relationship is such that when operation of cord 35 tends to move the pulley units towards each other, the locks 10 of both units 2 tend to remain in their lock positions L (FIGURE 2), and are not shifted to their release positions R.

Various embodiments of the present invention, in addition to what has been illustrated and described in detail, may be employed without departing from the scope of the accompanying claims.

I claim:

1. For use in a drapery-operating system including a pull cord, and a hollow traverse rod having a downwardly-facing longitudinal slot, a releasably-lockable end-pulley unit positionable longitudinally on the traverse rod to facilitate operation of the pull cord and to make possible the accommodation of draperies of various

widths on a traverse rod of given length, the said end-pulley unit comprising: a frame slidably mountable in the longitudinal slot of the traverse rod, and having a body portion depending beneath the slot; a first pulley wheel mounted rotatably on the depending body portion of the frame and having an upper arc rising at least to a plane common to the opposing edges of the slot; a second pulley wheel mounted rotatably on the depending body portion of the frame in coplanar relation with the first wheel and having an upper arc rising above the upper arc of the first wheel; and a cam lock mounted pivotally on the frame to lock the same at a desired position on the traverse rod.

2. For use in a drapery-operating system including a pull cord, and a hollow traverse rod having a downwardly-facing longitudinal slot, a releasably-lockable end-pulley unit positionable longitudinally on the traverse rod to facilitate operation of the pull cord and to make possible the accommodation of draperies of various widths on a traverse rod of given length, the said end-pulley unit comprising: a channel-shaped frame having a width slightly less than the width of the longitudinal slot, said frame having mounting flanges extending laterally therefrom to engage the interior surface of the traverse rod adjacent said slot, so that the frame will have a depending body portion beneath the slot and will be slidable longitudinally along the traverse rod; a first pulley wheel mounted rotatably on the depending body portion of the frame and having an upper arc rising at least to a plane common to the opposing edges of the slot; a second pulley wheel mounted rotatably on the depending body portion of the frame in coplanar relation with the first wheel and having an upper arc rising above the upper arc of the first wheel; a cam lock mounted pivotally on the depending body portion of the frame externally of the traverse rod, said cam lock having an effective radius greater than the distance between the pivotal axis of the cam lock and a point of engagement between the cam lock and the traverse rod; and a laterally-extending drapery bar coupled detachably to the depending body portion of the frame.

3. The invention as claimed in claim 2, in which said drapery bar is adapted to project from either side of said frame.

4. The invention as claimed in claim 2, in which said cam lock has a tooth portion adapted to bite into said traverse rod upon pivotal movement of said cam lock relative to said frame, and also has a stop means disposed to prevent overtravel of said tooth portion relative to said traverse rod.

5. For use in a drapery-operating system including a pull cord, and a hollow traverse rod having a downwardly-facing longitudinal slot, a releasably-lockable end-pulley unit positionable longitudinally on the traverse rod to facilitate operation of the pull cord and to make possible the accommodation of draperies of various widths on a traverse rod of given length, the said end-pulley unit comprising: a channel-shaped frame having a width slightly less than the width of said longitudinal slot, said frame having mounting flanges extending laterally therefrom to engage the interior surface of the traverse rod adjacent said slot, so that the frame will have a depending body portion beneath the slot and will be slidable longitudinally along the traverse rod; pulley-wheel means mounted rotatably in said depending body portion of said frame and adapted to receive said pull cord, said pulley-wheel means being disposed in a plane which is parallel to a plane containing the axis of said

track and extending through said slot; and lock means mounted on said frame to engage said traverse rod at any desired point therealong and prevent longitudinal movement of said frame relative to said traverse rod.

5 6. The invention as claimed in claim 5, in which said lock means is adapted in conjunction with at least one of said mounting flanges to grip against the exterior and interior surfaces of a traverse rod edge adjacent said slot.

7. The invention as claimed in claim 5, in which a drapery bar is mounted on said depending body portion of said frame.

8. A traverse rod assembly, which comprises a hollow track having a slot or gap along one side thereof, a frame having a supporting portion disposed interiorly of said track and a pulley-mounting portion extending through said slot to the exterior of said track, said supporting portion having a transverse dimension greater than the width of said slot whereby said supporting portion will rest on the opposed edges of said track adjacent said slot, said frame being slidable longitudinally of said track, means to lock said frame at various desired positions along the length of said track, pulley-wheel means rotatably mounted on said pulley-mounting portion of said frame in a plane which contains the axis of said track and extends through said slot, and pull-cord means extending through said track longitudinally thereof and riding on said pulley-wheel means.

9. The invention as claimed in claim 8, in which said supporting portion of said frame is engaged with interior portions of said track edges adjacent said slot, and in which said lock means is a cam element mounted on said pulley-mounting frame portion and manually movable into gripping engagement with exterior portions of said track edges adjacent said slot, said cam element being disposed exteriorly of said track.

30 10. The invention as claimed in claim 9, in which said cam element is pivotally mounted on said pulley-mounting portion of said track, and is formed with locking teeth adapted to bite into said track.

40 11. The invention as claimed in claim 8, in which a second and corresponding frame, pulley-wheel and locking assembly is mounted on said track, and in which a drapery-support bar is secured to each of said frames in laterally-extending relationship.

45 12. A traverse rod assembly, which comprises a hollow track having a slot or gap along one side thereof, a frame slidable longitudinally of said track, manually-operable means to lock said frame at any desired position along the length of said track, pulley-wheel means rotatably mounted on said frame, said pulley-wheel means lying in a plane which contains the axis of said track and extends through said slot, and pull-cord means extending through said track longitudinally thereof and riding in said pulley-wheel means, said pull-cord means also extending through said slot from the interior of said track to the exterior thereof.

50 13. The invention as claimed in claim 12, in which said pulley-wheel means is disposed at least partially in said slot whereby to insure guiding of said pull cord therethrough without contacting the edges of said track.
